UNITED STATES PATENT OFFICE.

FLOYD SMITH, OF SAN DIEGO, CALIFORNIA.

WATER-BOMB.

1,391,800.

Specification of Letters Patent. Patented Sept. 27, 1921.

Application filed November 1, 1917. Serial No. 199,679.

To all whom it may concern:

Be it known that I, FLOYD SMITH, a citizen of the United States, residing at San Diego, in the county of San Diego, State of California, have invented new and useful Improvements in Water-Bombs, of which the following is a specification.

This invention relates to bombs adapted to be exploded under water, or adapted to be exploded by virtue of having passed a certain distance through a fluid (not necessarily a liquid); and in its more specific aspects this invention relates to a bomb adapted to be dropped through the atmosphere into water and adapted to explode upon reaching a certain depth of water.

In a typical embodiment of my invention I employ a means actuated by passage of the bomb through a fluid to detonate the bomb. And, in a typical specific embodiment of my invention, I make this means actuatable by water in such a manner that when the bomb has passed through a certain depth of water it will then be exploded. With this means I also combine an arrangement whereby the bomb may be exploded by contact if it should strike an object before it has passed through the predetermined depth of water. Furthermore, in this preferred specific embodiment of my invention, I employ, in combination, a means for moving the detonator into operative relation with the explosive charge, said means being actuated by virtue of the dropping of the bomb through the atmosphere. Thus in preferred form, my bomb includes an explosive charge, a detonator normally out of operative relation to the explosive charge, and an air operated means for moving the detonator into operative position; and a water operated means adapted to set off the detonator after a certain amount of movement through the water; with means provided for contact detonation. This typical specific preferred form of bomb I explain in the following specification, reference being had for this purpose to the accompanying drawings in which—

Figure 1 is a vertical longitudinal section of my improved bomb, parts being shown in elevation; Fig. 2 is an enlarged longitudinal section of the upper tail end portion of the bomb; Fig. 3 is a detail cross section taken as indicated by line 3—3 on Fig. 2; Fig. 4 is a longitudinal section of the lower head portion of the bomb.

In the drawings the numeral 10 designates a bomb body which may be made in any approved design and structure to carry the explosive charge in its chambers 11 and 12. It may have stabilizing fins 10^a. Near the tail end of the bomb I may place a cross wall 13 to form the upper end of chamber 12; and the detonator 14 normally lies in position above this cross wall out of immediate proximity to the explosive charge in chamber 12 and entirely out of proximity to the booster 24 which is situated at an effective point within the body of the bomb. A longitudinal central tube 15 extends the length of the bomb body, being screw threaded in the lower or head end of the bomb at 16. Through the upper part of this tube I extend a screw rod 17 upon which the detonator 14 is screw-threadedly mounted; so that rotation of the rod will cause longitudinal movement of the detonator, the detonator being prevented from rotating by means of a lug 18 engaging in a longitudinal groove 19 on the interior of the tube 15. The screw rod 17 is mounted in a bearing 20 of any suitable character at the upper end of the bomb body; and the rod carries an air screw 21 whose blades 22 are set at a relatively slight angle. When the bomb is dropped through the atmosphere, the air screw and screw rod 17 are rotated in such a direction as to move the detonator downwardly from the position shown in Figs. 1 and 2 to the position shown in Fig. 4, where the detonator comes against a stop 23. In its lowermost position the detonator is opposite and is in register with the booster 24. The detonator comprises a body 25, screw threaded upon the rod 17, and carries an annular body of fulminate at 26 and annular primer cap at 27, firing channels being provided at 28 between the primer cap and the body of fulminate. In the position shown in Fig. 4, the body of fulminate is directly opposite the annular opening or port 29 which leads to the annular chamber 30 in booster 24, which annular chamber 30 contains a charge of material adapted to augment and reinforce the explosion of the detonator and to make sure the detonation of the explosive charge contained in the body of the bomb.

When the detonator has reached a position shown in Fig. 4, it is ready to be exploded to explode the charge of the bomb; and it may be exploded by the upward move-

ment of a firing plunger tube 35. This firing tube may be operated in either of two manners; either by actuation from a water screw 36 or by contact actuation of plunger 37. The mechanisms which cause these actuations will now be set forth.

- Firing tube 35 is mounted in a block 38 which slides in tube 15 and is normally held down by a light spring 39. Block 38 carries 10 a pair of pawls 40 whose ends project downwardly and outwardly over a heavy firing spring 41. The pawls 40 are normally prevented from moving upwardly by the fact that they pass through slots 42 in a sleeve 15 43 mounted upon stationary part 48. Spring 41 tends to press the pawls 40 upwardly; but the sleeve 43 cannot move upwardly under normal conditions, because the lower end of plunger 37 is screw threaded at 20 45 and the hub 46 of water screw 36 has a lug or lugs 47 engaging the screw threads 45. The water screw is mounted upon a bearing sleeve 48 and is adapted to be rotated in such a direction as to move plunger 37 upwardly against block 38, being slotted at 25 37° to accommodate pawls 40. When water screw 36 has rotated a sufficient amount, the block 38 will be moved up slightly and the pawls 40 will be pulled upwardly and 30 inwardly sufficiently to release the spring 41. Spring 41 will suddenly press upwardly on block 38, moving firing tube 35 in upwardly to strike the primer cap 27, causing 35 explosion of the detonator and thus causing explosion of the booster and explosion of the charge contained in the bomb. It will be seen that the detonator cannot be exploded except when it is in the position shown in Fig. 4; and it is moved to this position by the fact that the bomb has dropped 40 a certain distance through air. The water propeller 36 cannot be moved by air action; it moves with too great difficulty for that, because it must move against the force of 45 spring 39, and against the action of spring 41 in pawls 40; whereas the air screw 21 is easily moved. It follows, therefore, that this particular type of bomb must pass a certain distance through water before it is 50 detonated. The distance may be regulated by regulating the longitudinal position of plunger 37 and regulating the amount of rotation required to draw the pawls 40 off spring 41. Spring 39 is provided merely 55 for the purpose of holding down the pivoted end of pawls 40 and holding the firing tube 35 down.
- If the plunger 37 should strike an object before the water screw action has taken 60 place, then the plunger may be forcibly moved upwardly. Lugs 47 engaging screw threads 45 are made of such strength as to be sheared off by any forcible striking of plunger 37; and in such case the plunger 65 37 and tube 43 will be moved upwardly,

moving the block 38 and firing tube 35, causing firing tube 35 to strike the primer cap 27.

I have explained and claimed in a co-pending application, Serial No. 199,678, filed November 1st, 1917, such an air actuated detonator moving means as is herein set forth; and I do not herein particularly claim said means alone. In features wherein the means and combinations herein are the same as in said co-pending application, the broad claims are included in said application. Otherwise, the structure shown herein is claimed herein. For instance, in said application the firing mechanism is always in operative relation to the detonator; in this application the detonator is moved into such relation. And the means for exploding the detonator is a distinctive feature of the present invention, said means being operated by virtue of passage of the bomb a given distance through a fluid, specifically, water; and I herein claim such means both in combination with the air actuated detonator moving means, and in combination with the other features herein described. Within such limits I regard my invention as being broad in nature and not limited to the particular and specific details of structure herein set forth; intending the following claims to cover the invention broadly, as well as specifically, and to include all of those changes which may suggest themselves to those skilled in the art. And, within the limits of structure expressed in the following claims I intend my invention to be applicable to all sorts of explosive devices and not limited to the specific form of water bomb adapted to be dropped from aircraft which is here explained as the preferred embodiment of my invention.

Having described a preferred form of my invention, I claim:

1. In a bomb, the combination of a body having a chamber for an explosive charge, a detonator, and firing mechanism for the detonator including a firing member adapted to strike the detonator, a plunger adapted to move the firing member, a spring adapted to move the firing member, means controlled by the plunger to lock the spring, and a propeller screw adapted by its rotation to move the plunger to release the spring.

2. In a bomb, the combination of a body having a chamber for an explosive charge, a detonator normally outside the chamber and movable thereinto, an air propeller screw adapted to move the detonator into the chamber, and a water propeller screw adapted to explode the detonator.

3. In a bomb, the combination of a body having a chamber for an explosive charge, a detonator normally outside the chamber and movable thereinto, an air propeller screw adapted to move the detonator into the chamber, and firing mechanism for the det-

onator embodying a contact operated means and a means operated by passage of the bomb through water.

4. In a bomb, the combination of a body having a chamber for an explosive charge, a detonator normally out of operative relation to the charge and movable into such relation, a firing mechanism for the detonator with which the detonator is normally out of operative relation, and means for moving the detonator into operative relation with the charge and with the firing mechanism.

5. In a bomb, the combination of a body having a chamber for an explosive charge, a detonator normally out of operative relation to the charge and movable into such relation, a firing mechanism for the detonator with which the detonator is normally out of operative relation, and air propeller screw means for moving the detonator into operative relation with the charge and with the firing mechanism.

6. In a bomb, the combination of a body having a chamber for an explosive charge, a detonator normally out of operative relation to the charge and movable into such relation, a water propeller screw operated firing mechanism for the detonator with which the detonator is normally out of operative relation, and means for moving the detonator into operative relation with the charge and with the firing mechanism.

7. In a bomb, the combination of a charge holding body and firing mechanism for the charge including an actuating element adapted to be operated by the fluid through which the bomb travels, and including means yieldingly opposing the operation of said element so that the element can be operated by liquid but not by the atmosphere.

8. In a bomb, the combination of a charge holding body, a detonator normally out of operative relation to the charge, means actuatable by passage through the air to put the detonator into such operative relation, and separate means actuatable by passage through water to explode the detonator.

9. In a bomb, the combination of a charge holding body, a detonator normally out of operative relation to the charge, means for putting the detonator into such operative relation, and separate means actuatable by passage through water to explode the detonator.

55 10. In a bomb, the combination of a charge holding body, a detonator normally out of operative relation to the charge, means for putting the detonator into such operative relation, and separate means actuatable by passage through the fluid through which the bomb travels to explode the detonator.

11. In a bomb, the combination of a charge holding body, a detonator normally out of operative relation to the charge, means for putting the detonator into such operative re-

lation, and separate means for exploding the detonator including an actuating element adapted to be operated by the fluid through which the bomb travels and including a member adapted to be actuated by contact with any exterior body.

12. In a bomb, the combination of a charge holding body, a detonator for the body, firing means for the detonator, the detonator and firing means being normally out of operative relation to each other, means to positively put the detonator and firing means into operative relation to each other, and means to cause operation of the firing means.

13. In a bomb, the combination of a charge holding body, a detonator for the body, firing means for the detonator, the detonator and firing means being normally out of operative relation to each other, means actuated by passage of the bomb through a fluid to positively put the detonator and firing means into operative relation to each other, and means to cause operation of the firing means.

14. In a bomb, the combination of a charge holding body, a detonator for the body, firing means for the detonator, the detonator and firing means being normally out of operative relation to each other, means actuated by passage of the bomb through air to put the detonator and firing means into operative relation to each other, and means actuated by passage of the bomb through water to cause operation of the firing means.

15. In a bomb, the combination of a charge holding body, a detonator for the charge, firing means for the detonator, the detonator and firing means being normally out of operative relation to each other, air actuated means to move the detonator into operative relation to the firing means, and separate means actuated by passage of the bomb through water to cause operation of the firing means.

16. In a bomb, the combination of a charge holding body, a detonator for the charge normally out of firing relation to the charge, means to positively move the detonator into firing relation to the charge, a firing mechanism for the detonator operable when the detonator is moved into firing relation to the charge, said mechanism comprising a firing member adapted to contact with the detonator, a plunger adapted to move the firing member, a spring held normally locked and adapted to be released and impinge on the firing member when the latter is moved by the plunger, and a water screw propeller adapted to actuate the plunger.

In witness that I claim the foregoing I have hereunto subscribed my name this 26th day of October, 1917.

FLOYD SMITH.

Witness:

JAMES T. BARKELEW.
